UNITED STATES PATENT OFFICE.

WILLIAM J. LEIGHTY, OF SPRINGFIELD, MISSOURI, ASSIGNOR OF ONE-HALF TO
HENRY W. JACOBS, OF CHICAGO, ILLINOIS.

LOCOMOTIVE-FIREBOX.

1,369,117.

Specification of Letters Patent. Patented Feb. 22, 1921.

Application filed October 28, 1915. Serial No. 58,399.

To all whom it may concern:

Be it known that I, WILLIAM J. LEIGHTY, a citizen of the United States, and resident of Springfield, in the county of Greene and State of Missouri, have invented certain new and useful Improvements in Locomotive-Fireboxes, of which the following is a description, reference being had to the accompanying drawings, which form a part of my specification.

My invention relates to locomotive fireboxes of the water-tube type provided with water-chambers or drums arranged along the bottom or lower sides of the firebox, in addition to the usual water-space or chamber above the crown of the firebox; the water-spaces or chambers being connected by water-conveying members or tubes arranged in such a manner as to materially enhance the steaming capacity of the firebox.

The object of my invention is to provide a firebox whereby the danger of explosion will be reduced to a minimum degree; at the same time provide a firebox that is simple in construction, strong in design and inexpensive to manufacture.

The purpose of my invention is to produce a firebox wherein the water-tubes which connect the mud-drum or lower water-spaces or chambers with the crown-sheet, or rather with the water-space above the crown-sheet, are vertically disposed so as to constitute tubular side walls for the firebox; while certain of the tubes are so arranged as to constitute an arch at the forward end of the firebox; the construction and arrangement of the water-tubes being such, however, as to permit a free flow or circulation upward through the water-tubes between the lower water-spaces or mud-drum and the water-space or chamber above, the crown sheet; the water-tubes being so arranged as to provide a firebox which is very efficient in fuel consumption.

The advantages of my invention, which are inherent in the construction disclosed, will be more fully comprehended from the following detailed description of the drawings wherein:

Figure 1 is a longitudinal sectional view of the preferred form of my invention; the

figure disclosing the peculiar arrangement or disposition of the water-tubes.

Fig. 2 is a vertical cross section, taken on the line A—A of Fig. 1, looking in the direction of the arrows, and more clearly disclosing the transverse arrangement or disposition of the water-tubes which compose a portion of the side walls of the firebox as well as a tubular arch.

Fig. 3 illustrates a modified form of my invention; the figure being a partial side elevation and partial longitudinal section, disclosing the construction and arrangement of the outer structure as well as the disposition of the water-tubes arranged to constitute the inner side walls of the firebox.

Fig. 4 is a partial rear end elevation and partial vertical sectional view taken on the line B—B of Fig. 3, looking in the direction of the arrows, and disclosing the arrangement of the water-tubes as well as the construction of the lower water-spaces or mud-drums.

Fig. 5 is a sectional plan view of my improved construction as illustrated in Figs. 1 and 2; the view being taken just above the lower water spaces or mud-drums, as shown in Fig. 2, with the water-tubes removed and the throat-sheets, flue-sheet, door-sheet and back head shown in section.

Fig. 6 is a detail perspective view of the upper left-hand corner of the construction shown in Fig. 5; the view illustrating the construction in up-ended position in order to give a clearer view into the water space and disclose the reinforcing lug.

In the particular exemplification of my invention as disclosed in Figs. 1 and 2, the crown-sheet of the firebox is preferably composed of a number of transversely arranged channel sections 5 having their sides or flanges vertically disposed into the water-space or chamber of the firebox. The adjacent sides or flanged portions of the sections 5 of the crown-sheet are preferably provided with intervening stay-sheets or calking strips 6 and secured together by means of the rivets 7.

The stay-sheets or strips 6 secure the sections of the crown-sheet to the roof-sheet 8 in the manner more clearly shown in Fig. 1, wherein the upper ends of the stay-sheets 6

are preferably secured between the angle-irons or members 9 by the rivets 10; the angle-irons or members 9 being shown secured to the roof-sheet 8 by the rivets 11. In 5 this manner the transversely arranged sections of the crown-sheet are supported from the roof-sheet in a very secure and, at the same time, economical manner.

The transversely arranged crown-sections 10 5 extend only part way across the central part of the crown of the firebox, as shown in Fig. 2, and have their ends contact with the semicircular side sections 12 of the crown sheet, to which they are secured in any suitable manner, but preferably by means of a 15 serrated welded seam, as indicated at 13; the seam or weld being made in any suitable manner as, for example, by the autogenous method. By employing the serrated seam as 20 herein disclosed, the efficiency of the welded joint is made equal to the strength of the rolled material in the direction of the strains to which the sections are subjected.

The semicircular sections or portions 25 12 of the crown-sheet, which are preferably welded as described to the crown-sheet channel-sections, have their opposite sides secured to the roof-sheet 8 preferably by means of the riveted seams 14.

30 The semicircular sections 12, 12 of the crown-sheet receive the upper ends of the different series of water-tubes 15, 16 and 17, see Fig. 2; the tubes constituting the series 35 17 and connected with the semicircular sections 12 being lead from the side of the firebox opposite to that on which the respective semicircular crown-section of the firebox is located.

30 The stay-sheets 6 are so formed or cut 40 away at their sides as to provide a large space or cavity between the stay-sheets and the semicircular sections 12 of the crown-sheet, in order to permit the entrances of a man above the crown-sheet, for the purpose 45 of making any necessary repairs of the tube connections with the crown-sheet.

In the particular exemplification the longitudinal sections of the mud-drum are formed to constitute water-spaces or chambers along the lower sides of the firebox, and 50 preferably consist of separate transversely bent or curved members or walls 18, 18, 19 and 20. The members or walls 18 are secured at their forward ends in any suitable 55 manner to the flue-sheet 21, while the rearward ends of members or walls 18 are properly secured to the door-sheet 22. The members or walls 18 constitute the inner sides of the longitudinal sections of the mud-drum 60 and are adapted to receive the lower ends of the different series of water-tubes 15, 16 and 17; the water-tubes being secured to the members or walls 18 in any suitable manner as rolling, beading and pressing or welding. 65 By arranging the member or wall 18 of the

longitudinal sections of the mud-drum in the sloping or diagonal manner, the joints between the two members or walls are located on the outer surface of the firebox and at the same time sufficient surface for the ends 70 of the water-tubes is provided; the series of water-tubes 15 being thus arranged to practically constitute the side wall proper of the firebox. The construction and arrangement 75 also enables the tubes to be spaced apart a sufficient distance to give a substantial bridge in the mud-drum as well as in the crown-sheet.

The members or walls 19 and 20, which 80 constitute the outside walls of the longitudinal sections of the mud-drum, have their sides secured to the sides of the inner wall 18 by means of suitable joints 23 and 24, as can more clearly be seen in Fig. 2. The outer walls or members of the longitudinal sections 85 of the mud-ring may be provided with suitable hand-holes, as shown for example at 25, in Fig. 2, to enable access being had to the chambers or longitudinal sections of the mud-drum. In view, however, of the peculiar construction and arrangement of the longitudinal sections of the mud-drum, the hand-holes may be omitted if desired.

The solid or transverse section 26 of the mud-drum, at the forward end of the firebox, 90 is preferably provided with upwardly extending lugs 27 at the end thereof, so as to reinforce the flue-sheet 21 which may be secured thereto by means of rivets 28, see Fig. 2. The solid transverse section 29 at the 100 rearward end of the firebox is also shown provided with upwardly presented projections 30, at both ends of said section, in order to reinforce the door-sheet 22.

As is evident from the construction shown, 105 the water has free circulation from the front water leg, formed between the flue-sheet 21 and the throat-sheet 31, to the back water-leg, formed intermediate of the door-sheet 22 and the back-head 32, by means of the 110 hollow longitudinal sections of the mud-ring arranged at the lower sides of the firebox. The construction shown and described permits complete circulation over the top and bottom of the firebox, in the usual manner, 115 as the rear end of the firebox is composed of the usual door-sheet and back-head common to locomotive boiler practice.

The spaces between the tubes 15 are shown 120 filled with firebrick 33, see Fig. 2; the fire-brick, in turn, is shown covered with the lagging 34 which is preferably provided with a sectional covering of metallic sheets 35, which may be secured in place in any suitable manner, as, for example, by the 125 angle-irons or bars 35, bolted or otherwise secured together. The fire-brick, lagging and sectional plates or outer covering extends from a point intermediate of the semicircular sections 12 of the crown-sheet and 130

the uppermost portion of the longitudinal hollow sections of the mud-drum, as shown in Fig. 2, and thus provides a gas tight wall for the sides of the firebox which will prevent the escape of the gases of combustion except, of course, through the fire-tubes or flues in the flue-sheet 21.

The water-tubes 16 are inclined upwardly and inwardly and at a distance removed 10 from the water tubes 15, with the ends of the water-tubes 16 connected with the semi-circular sections 12 and the inner walls 18 of the mud-drum located on the same side of the firebox. The water-tubes 17, which are 15 located at a distance forward of the door-sheet or rear end of the firebox, are arranged to extend from the longitudinal section of the mud-drum on one side of the firebox in a slightly curved manner transversely of the 20 firebox to the semi-circular section of the crown-sheet located on the opposite side of the firebox. The water-tubes of the series 17 are so arranged or spaced apart as to 25 permit the crossing of the tubes substantially at the longitudinal center line of the firebox; and the bend or inclination of each succeeding tube of this series is at such 30 point, relative to the ends of the tube, that the tubes will provide a rearwardly ascending 35 self-supporting arch, as very clearly shown in Fig. 1. It will be seen that the tubes are inclined and bent so as to cross each other adjacent the lower part of the firebox in the front end thereof, while the 40 bend or inclination of each succeeding tube is arranged in a slightly higher plane, so 45 that the bend or inclination of the last tubes of this series will be at a point slightly removed from the crown-sheet, as shown in Fig. 1. The arrangement of the water-tubes, as disclosed and described, provides a very 50 efficient heating surface because the tubes extend into the path of the gases, without, however, impairing the circulation or flow 55 of the gases of combustion within the firebox; the gases, as will be seen, being free 60 to pass about the tubes.

The tubes 17, which are arranged to constitute an arch, may be covered with fire-brick 36 and 37, as shown to the right in Fig. 2, so as to form a brick arch within the firebox. The brick arch may be omitted if desired. By employing the brick arch, the 55 gases of combustion will pass upward about the water-tubes 17 and into the space between the tubes 17 and the transversely arranged sections of the crown-sheet, so that the tubes 16 and 17 will be completely surrounded by the hot gases of combustion, 60 thereby providing a great amount of heat absorbing surface. The arrangement of these tubes also tends to break up the intense heat of the fire and prevent it from striking directly against the tubes 15 which constitute the side walls of the firebox.

The different series of tubes arranged as shown and described, so as to connect the crown-sheet with the hollow longitudinal sections of the mud-drum, provide for the vertical circulation of the water from the 70 mud-drums to the water-space above the crown-sheet, which will prevent the water-tubes from becoming overheated; at the same time providing a maximum amount of heating surface directly exposed to the hot gases 75 of combustion within the firebox.

In the particular exemplification of the invention, the flue-sheet 21 is shown provided with the offset 38 at the upper or crown-portion thereof, and with the offset 80 80 portion 39 along the sides, see Fig. 1, thus insuring the necessary flexibility to take up expansion in all directions. The door-sheet 22 is shown provided with a double offset 40 adjacent the upper or crown-portion thereof 85 and with the offset 41 along the sides, thus also permitting this sheet to take up any expansion which may occur.

The connection between the door-sheet 22 and the back-head 32 may be made in any 90 suitable manner at the door-opening thereof, being preferably formed by an autogenous weld, as shown at 42 in Fig. 1; the sheets being also secured or connected together throughout their paralleling flat surfaces by 95 means of the stay-bolts 43. The flue-sheet 21 and the throat-sheet 31 are also connected together throughout their paralleling surfaces by means of the usual stay-bolts 44, 100 see Fig. 1.

The back-head 32 of the firebox is shown provided with hand-holes, as at 45 in Fig. 1, for the purpose of giving access to the water-space above the crown-sheet; the hand-holes being preferably located in alignment with the enlarged space intermediate of the ends of the stay-sheets 6 and the semi-circular sections 12 of the crown-sheet. By reason of the hand-holes (which are 105 provided with suitable covers) inspection of 110 the interior or water-chamber portion of the firebox may be had.

In order to further support the back-head of the firebox at the upper end thereof, I provide the stay-rods 46 (see Fig. 1) which 115 extend lengthwise of the upper end of the firebox and are connected at their forward ends in any well known manner to the shell of the boiler at a point forward of the firebox; the rear ends of the stay-rods or bolts 46 being shown connected with the anchor 120 47, shown riveted to the back-head; the anchor 47 being preferably a steel casting.

It is evident from the drawings and description that a very strong construction is 125 provided.

The crown-sheet and the mud-drums are provided with the usual washout openings 48 and 49, respectively.

I have shown and described what I believe 130

to be the simplest and best forms of my invention, but the constructions may be altered in certain minor details without, however, departing from the spirit of my invention.

I do not wish to be understood, therefore, as limiting myself to the exact constructions shown and described.

What I claim is:—

- 10 1. In a locomotive firebox of the class described, provided with a crown sheet and mud-drums at the lower bottom longitudinal sides of the firebox, a plurality of self-supporting water-tubes arranged in series intermediate of the crown sheet and the mud-drums, one series of tubes on each side of the firebox being arranged diagonally between the mud-drum at the bottom on one side of the firebox and a portion of the 15 crown sheet on the opposite side of the firebox and at a distance removed from the front and rear ends of the firebox, with the oppositely disposed tubes of said series crossing one another at substantially the longitudinal center line of the firebox, the point of crossing of the successive tubes being at an increasing distance removed from the bottom of the firebox from front to rear thereof so as to form a gas-deflecting arch 20 intermediate of the front and rear end of the firebox.

2. A locomotive firebox of the class described, provided with a crown-sheet, mud-drums at the bottom longitudinal sides of 35 the firebox, and a plurality of water-tubes extending from the mud-drums to the crown-sheet, a portion of said water-tubes being arranged to constitute the inner side walls of the firebox, while the other portion of 40 said water-tubes extend upwardly in a sloping manner from the mud-drum on one side of the firebox to a portion of the crown sheet on the opposite side of the firebox, the water-tubes of said last mentioned portion 45 being arranged to cross substantially at the longitudinal center line of the firebox, with the crossing of each succeeding water-tube, from front to rear, being in a higher horizontal plane and providing a self-supporting 50 water-tube arch.

3. In a locomotive firebox, the combination of a crown-sheet and mud-drums arranged longitudinally along the lower sides of the firebox, with a plurality of upwardly disposed water-tubes arranged in groups intermediate of the crown-sheet and the mud-drum, one group of said tubes being arranged to constitute the inner side walls of the firebox, the tubes of a second group sloping upwardly in a diagonal manner from the mud-drum on one side of the firebox to a portion of the crown sheet on the opposite side of the firebox, the tubes of said group leading from opposite mud-drums being arranged to cross one another substantially at the longitudinal center line of the firebox and at a higher horizontal plane from front to rear of the firebox providing a self-supporting gas-deflecting water-tube arch, while a third group of said water-tubes are arranged intermediate of the first and second groups.

4. In a locomotive firebox, the combination of a crown-sheet and water-spaces arranged along the lower longitudinal sides of the firebox, with a plurality of upwardly disposed water-tubes arranged in groups intermediate of the crown-sheet and said water-spaces, one group of said tubes being arranged to constitute the inner side walls 80 of the firebox intermediate of said water-spaces and the crown-sheet, the tubes of the second group sloping upwardly in a diagonal manner from the lower water-space at one side of the firebox to a portion 85 of the crown-sheet on the opposite side of the firebox, the tubes of said group leading from opposite sides being arranged to cross one another substantially at the longitudinal center line of the firebox and at a higher 90 horizontal plane from front to rear of the firebox and providing a self-supporting gas-deflecting water-tube arch, while a third group of said water-tubes are arranged intermediate of the first and second groups.
